(57) **CLAIM**

The ornamental design for a golf ball container, as shown and described.

DESCRIPTION

FIG. 1 is a front elevational view of the golf ball container of my design;

FIG. 2 is a rear elevational view thereof;

FIG. 3 is a side elevational view of the right side thereof;

FIG. 4 is a side elevational view of the left side thereof;

FIG. 5 is a top plan view thereof; and,

FIG. 6 is a bottom plan view thereof.

The broken line showing of the bottom is for illustrative purposes only, and forms no part of the claimed design.
